UNITED STATES PATENT OFFICE.

ALLAN C. SARGENT AND FRANK L. FURBUSH, OF WESTFORD, MASSACHUSETTS, AS
SIGNORS TO C. G. SARGENT'S SONS CORPORATION, OF GRANITEVILLE, MASSACHU-
SETTS, A CORPORATION OF MASSACHUSETTS.

BURR PICKER.

Application filed October 1, 1924. Serial No. 741,028.

To all whom it may concern:

Be it known that we, ALLAN C. SARGENT and FRANK L. FURBUSH, both citizens of the United States, residing at Westford, in the 5 county of Middlesex and State of Massachusetts, have invented a new and useful Burr Picker, of which the following is a specification.

This invention relates to a burr picker 10 and although capable of general use it is especially adaptable to the so-called multiplex burr picker which has been on the market for a good many years and it is shown in the accompanying drawing as applied thereto.

The principal objects of the invention are to provide adjustable means adjacent to the brush of such a machine to prevent the air draft from pulling the stock back around the brush, this means being made adjustable to provide for the wear on the ends of the brush bristles; to provide adjustable deflecting means located at either side of the upper burr separator to prevent small shives and 25 flyings from the stock being carried around by the burr separator and deposited on the other side of the adjacent burr cylinder so as to be allowed to go through with the finished stock, but at the same time to arrange the deflector so that a certain amount of air can be taken in at this point; to provide a steel cut-off or deflector at the side of the burr receptacle adjustable so as to leave an opening of the proper size to insure that 30 the larger and heavier burrs when knocked off the stock by the second burr separator will be discarded and allowed to slide down out of the machine; and to provide a register over the second burr separator for regulating the amount of air that can be taken in past that separator to help impale the stock on the second burr cylinder.

Other objects and advantages of the invention will appear hereinafter.

Reference is to be had to the accompanying drawing, which is a longitudinal central sectional view of a multiplex burr picker with a preferred embodiment of this invention applied thereto.

The invention is shown, as stated, as applied to a type of burr picker in which the wool or other stock is fed into the machine on a feed apron 10 against the main cylinder 11. The wool is thoroughly picked

and subdivided in its transfer from one to 55 the other. The stock is carried downward by the main cylinder over a bottom rack 12 where the impurities, such as shives, oats, straws and the like, loosened by the opening action, are thrown out by centrifugal force 60 and sifted through the rack into the lower part of the picker.

The fiber is delivered from the main cylinder to the first burr cylinder 13. Here the 65 stock passes down between the wire teeth leaving burrs and other matters exposed on the surface. These are thrust out on the floor by a rapidly revolving burr separator 14. The stock then goes to the next burr cylinder 15 which rotates faster than the 70 first burr cylinder and takes up the stock into position to be acted on by the second burr separator 16 which has the same effect as the first one but on the other side of the stock. The stock is carried along on the cylinder 15 to the brush 17 where it is delivered from the machine in the usual way. What has been described in this paragraph is old in this art.

It will be understood, of course, that one 80 of the cleaning operations is performed by a fan or blower 18 located at the top of the picker or by securing the same result by means of a regular air intake at that point. The intake is located just over the second burr separator 16 in the form shown, but it can be applied to the only burr separator of one type of picker in accordance with the present invention. A pair of adjustable 85 steel cut-offs or deflectors 20 and 21 are provided secured to the intake at either side of it and of the burr separator 16. They extend throughout the width of the intake. This is for the purpose of preventing the 90 small shives and flyings taken up by this burr separator from being carried around by it and deposited back on the burr cylinder 15. The deflector 21 on the forward side is set farther away from the burr separator than the deflector 20 so as to allow a certain amount of air to be taken in at this point past the burr separator.

The amount of air passing through is 95 regulated by a register 22 located over the burr separator 16 and controlling the amount of air passing through. It consists of two perforated plates of ordinary form, one of them rotatable to vary the openings

23. Therefore it controls the force with which the stock is impaled on the burr cylinder 15, this being one of the functions of the draft of air through the picker.

5 The burrs thrust off by the second burr separator pass into the burr receptacle 25 which has a slanting floor 26 extending up to a point nearly between and tangent to the two cylinders 15 and 16. On the upper end 10 of this inclined floor is located an adjustable cut-off 27 consisting of a piece of steel extending across the whole length of the cylinders. This is adjusted so as to leave an opening of the proper size so that the larger 15 and heavier burrs knocked off the stock by the second burr separator 16 will be retarded and allowed to slide down the incline 26. Here they land on the bottom from which they are taken away by a conveyor 28. This bottom 26 is inclined at a 20 steep enough angle so that the burrs that are expelled from the wool and deposited on it slide down easily by gravity without the employment of mechanical means for causing 25 them to do so.

At the delivery end of the machine we also provide an adjustable steel cut-off plate 30 which is secured to the picker inside the top 30 of the outlet spout and is adjustable radially toward the brush 17. This cuts off the circulation of air outside the brush and deflects it through it and it is adjustable toward the brush as the tips of the bristles wear off to avoid the appearance of a wide space 35 through which the air draft would pull the stock back around the brush.

The cut-offs or deflectors 27 and 30 extend throughout the width of the machine and the length of the cylinders.

40 The sides of the machine are constructed so that the bearings can be either ball bearings or babbitted bearing boxes.

One of the cleaning actions which is an 45 important feature of the old burr pickers is caused by the exhaust fan 18 or some equivalent means of creating a strong air current which passes constantly into and through the burr picker. On account of this suction the dust and other impurities of a similar 50 character are extracted from the wool as it is passing through the various parts of the machine, taken up into the top of the machine and deposited in a dust receiver, not shown. This cleaning action takes place practically 55 throughout the course of the wool through the machine because of the attenuated condition of the lap on the main cylinder and, in fact, all the way through. It is very largely for regulating this current of air 60 that most of these improvements are made. They all have to do with the course of the current, as has been stated.

Although we have illustrated and 65 described only a single form of the invention and shown it as applied only to a single type

of burr picker we are aware of the fact that modifications can be made therein and that it can be applied to other types of burr pickers without departing from the scope of the invention as expressed in the claims. Therefore we do not wish to be limited to all the details of construction herein shown and described or to the particular type of burr picker illustrated, but what we do claim is:—

1. In a burr picker, the combination with a burr cylinder, a burr separator associated therewith, an air inlet to the top of the machine located directly over the burr separator, and means for drawing the air into the machine through said inlet, of a cut-off or deflector extending down on the side of the burr separator and spaced from the circumference of the separator to admit a certain amount of air past the separator, and means in the inlet above the burr separator for regulating the amount of air admitted.

2. In a burr picker, the combination with a burr cylinder, a burr separator associated therewith, an air inlet to the top of the machine located directly over the burr separator, and means for drawing the air into the machine through said inlet, of a cut-off or deflector on each side of the burr separator extending along the same parallel with each other, that on one side being spaced farther from the circumference of the separator than the other, whereby practically all the air passing through the inlet must pass by the burr separator, a receptacle for receiving the burrs from the burr separator, said receptacle having a slanting bottom extending up substantially to the bottom of the burr separator for receiving the burrs and delivering them, and an adjustable plate fixed to the upper end of said bottom to reduce the space between the bottom and the burr cylinder.

3. In a burr picker, the combination with a burr cylinder and burr separator and means for drawing the air through the machine from the vicinity of the burr separator, of a receptacle in position for receiving the burrs cast out by the burr separator having a slanting bottom extending up substantially to the bottom of the burr separator and provided with an adjustable plate on the end for regulating and controlling the space between the burr cylinder and the slanting bottom and controlling the air currents passing through said space.

4. In a burr picker, the combination with a burr cylinder, a burr separator associated therewith, an air inlet from the top of the machine located adjacent to the burr separator, and a fan or blower withdrawing the air from the machine at a point on the other side of said cylinder from said inlet, of a cut-off or deflector on each side of the burr separator extending along the same parallel

with each other, that on one side being spaced farther from the circumference of the separator than the other to admit a certain amount of air past the separator, a brush for receiving the lap from the burr cylinder and delivering it from the machine, and an adjustable cut-off plate located at the outlet of the machine adjacent to the circumference of said brush for the purpose of preventing currents of air induced by said fan or blower pulling the stock back around the brush.

5. In a burr picker, the combination with a burr cylinder, a burr separator associated therewith, an air inlet from the top of the

machine located adjacent to the second burr separator, and a fan or blower for withdrawing the air from the machine, of a brush for receiving the lap from the burr cylinder and delivering it from the machine, and an adjustable cut-off plate located at the outlet of the machine adjacent to the circumference of said brush for the purpose of preventing currents of air induced by said fan or blower pulling the stock back around the brush. 20

In testimony whereof we have hereunto affixed our signatures.

ALLAN C. SARGENT.
FRANK L. FURBUSH.
